UNITED STATES PATENT OFFICE.

LOUIS LONG, OF KANSAS CITY, KANSAS.

SAFETY TRAIN DEVICE.

1,101,299.

Specification of Letters Patent. Patented June 23, 1914.

Application filed October 29, 1908. Serial No. 459,620.

To all whom it may concern:

Be it known that I, LOUIS LONG, a citizen of the United States, residing at Kansas City, in the county of Wyandotte and State 5 of Kansas, have invented new and useful Improvements in Safety Train Devices, of which the following is a specification.

This invention relates to railway train controlling or safety devices, and has for an 10 object to provide a device of this character which may be installed along railway tracks at relatively low cost, and which will be automatic in its operation to control the air brake and throttle valves of trains approaching one another within a block, thus preventing head or rear end collisions.

With this and other objects in view as will appear as the description proceeds, the invention comprises the various novel features 20 of construction and arrangement of parts, which will be more fully set forth and described with particularity in the appended claims.

Referring to the drawings: Figure 1 is a 25 transverse sectional view through a railway track showing the application of the present invention thereto, parts being broken away to clearly illustrate the device, Fig. 2 is a vertical sectional view taken on the line 30 2-2 of Fig. 1, looking in the direction of the arrow, Fig. 3 is a top plan view showing some of the parts in section, Fig. 4 is a detail view of the clutch lever guide, Fig. 5 is an end view of the same, Fig. 6 is a trans- 35 verse section and rear view of a locomotive showing the mechanism carried thereby for coöperation with the sliding block, and the manner in which the wheels of a locomotive coöperate with the track mechanism, Fig. 7 is a vertical sectional view taken through the 40 sliding valve that is operated by the sliding block, Fig. 8 is a sectional view through the fluid cylinder showing the connections between its piston and the throttle valve lever, Fig. 9 is a detail side view of a locomotive, parts being broken away to show the locomotive carried means for coöperation with the sliding block, Fig. 10 is a detail view of the movable element for coen- 45 taging the sliding block and adapted to be operated to control the movement of the valve shown in Fig. 7, and Fig. 11 is a dia- 50 grammatic view of the track circuit and the block in which my device is arranged.

Similar characters of reference are used 55 to denote like parts throughout the drawings and in the accompanying specification.

Referring now more particularly to the drawings, there is shown the track rails A-B of a railway track of ordinary construction, between which is formed a pit for the reception of my improved safety train controlling device 10 which is preferably mounted in an inclosure 11 of metal or other suitable water proof material. The safety 60 device comprises horizontal shafts 12 and 13, the shaft 12 being mounted in bearings 14 and the shaft 13 being mounted in similar bearings 15. The shaft 12 has loosely mounted thereon a lifting member or arm 70 16, and the gear segments 17 and 18, the former of which is made integral with the arm 16. Extending through a longitudinal groove in the shaft 13 is a key 13' which locks a second lifting member or arm 19 75 similar to the arm 16, and the gear segments 20 and 21 which are adapted to mesh with the segments 17 and 18, respectively, against rotary motion upon the shaft. Extending from the rear of the gear segment 80 18 is an arm 51 that is provided with an adjustable counterbalancing weight 52.

A hollow casting of steel or other suitable block 22 rests at its lower end upon the members or lifting arms 16 and 19, and the 85 upper edge of this block is disposed adjacent to the rail A, and its upper face lies normally flush with the tread surface of the rail. Suitable guide members 23 are carried by the inclosure 11 and serve to hold 90 the block 22 in position upon the arms 16 and 19 and to produce a perfect sliding movement for said block. The segment 18 is loosely mounted upon the shaft 12 and has formed on its inner side a clutch element 24, 95 and slidably mounted upon the shaft is shown a similar clutch member 25 provided with an annular groove 26 for receiving the lower end of a vertically disposed arm 27 fulcrumed midway between its ends as indicated at 28, and at the upper end, this arm has pivotally mounted thereon a clutch lever 29 upon which is adjustably secured a weight 29'. This lever 29 carries a pin 30 at its outer end which is mounted to move 100 in vertical passages 31 and 32 formed in a guide 33 at the upper end of the bearing 14 adjacent to the rail B and in which bearing

is mounted one end of the shaft 12. The 5 guide has formed therein a horizontal passage 34 which receives a sliding pin 35 connected to the upper end of an armature 36 pivoted between its ends to a bracket secured to the guide 33. The pin is held in a withdrawn position by means of a helical spring 34^a which also serves to hold the lower end of said arm spaced from the core of an 10 electromagnet 35^a, when it is deenergized, and said magnet is supported upon a bracket 37 formed on the guide 33. The guide 33 is provided with a pair of arms 38 and 39, the arm 38 being pivoted at its lower end and 15 normally lies in a diagonal position across the slot 31 by means of a coil spring 40, and the arm 39 is pivoted at its upper end and extends in parallel relation to the arm 38 and across the slot 32, and is held in this 20 position normally by the spring 40^a similar to that just described.

A standard 41 is located adjacent to the electromagnet 35^a, and has formed thereon alining guides 42 for receiving a vertically 25 sliding bar 43 having a plurality of transversely disposed rack teeth 44 which mesh with the teeth of the pinion 45 keyed to the shaft 12, as illustrated. The bar 43 carries a depending pin or stem 46 around 30 which a helical spring 47 is coiled which serves to hold the bar normally in an elevated position. A pair of links 48 are pivoted at their inner ends to the bar 43 and are slotted adjacent to their outer ends for the 35 reception of studs 49 projecting from the rail B. A lifting hook 50 projects from the bar 43 and is disposed in a position to operate the clutch lever 29.

Arranged beneath the rail A adjacent the 40 movable block 22 is a solenoid 120 the core of which is connected with an extensible spring 121 that serves to move the core outwardly into engagement with the block 22 when the solenoid is deenergized, whereby 45 at the proper time, as will be explained later, the end of the core will seat within a recess 123 formed in one side of the block 22 to sustain the said block in an elevated position.

In Figs. 6 and 9, there is shown a locomotive C having the engineer's brake valve 50 52', the brake valve reservoir 53, and the usual form of brake mechanism 54 for engaging the main drive wheels as will be understood. A pump 55 having a steam cylinder 56 and an air cylinder 57 is provided, the cylinder 56 being connected with the steam dome, and the cylinder 57 being connected by way of a pipe 58 with the main reservoir, not shown.

60 The triple valve 59 is connected by means of a pipe 60 to a valve casing 61 beneath the locomotive. The said casing is preferably of rectangular form and has an open lower end as shown at 62. A pipe 63 connects the valve casing 61 with the brake

valve 52' and is disposed directly in line with the triple valve pipe 60 which enters the opposite side of the casing for a purpose to be hereinafter described. Also connected to the casing 61 and disposed directly in line beneath the pipe 63 are pipes 66 and 67, the pipe 66 leading to a fluid cylinder upon the engine boiler to be referred to later, and the pipe 67 serving as an exhaust to the atmosphere. A sliding valve 64 arranged within the casing 61 is provided at one side with a rectangular port 65 which normally establishes communication between the pipes 66 and 67. The valve 64 is further provided with a horizontally extending port 68 which extends from the upper end of the port 65 through to the other side of the valve. The pipe 66 leads to a fluid cylinder 70, mentioned above, in which a piston 71 is slidably mounted and which carries a piston rod 72 to the end of which is pivoted a link 73 having an angularly disposed finger 74. The link carried by the piston rod is pivoted to the throttle valve lever 75, and the finger 74 operates the clutch rod 76 to release it 90 when the throttle lever is to be moved to closed position. The cylinder 70 is also provided near its outer end with an exhaust port 70'.

The valve rod 77 secured to the lower end 95 of the valve 64 carries at its lower end an eccentric strap 78 engaged with an eccentric 79 upon a shaft 80. The shaft 80 has mounted thereon a revolvable element 81 in the form preferably of a wheel segment 100 which has upon its peripherial surface a band or a strip of leather, rubber or like material 82. It will thus be seen that the said element or wheel segment normally lies in a position beneath the locomotive to engage the block 22 previously referred to, when it is elevated above the plane of the rails so the said wheel or element can be turned sufficiently to force the valve 64 into an upward direction, as shown in Fig. 7 in dotted lines, 110 to allow air to be released from the train line, and consequently setting the brakes of an entire train.

When the valve 64 is in its normal position, as shown, direct communication is established between the triple valve pipe 60 and the brake valve pipe 63, and between the fluid cylinder 70, and the atmosphere through the pipe 66, port 65 and pipe 67 which acts as an exhaust for the cylinder 70 under normal conditions. Now when the valve 64 is raised connection is established from the train line through the medium of the triple valve pipe 60 and the brake valve pipe 63, by way of the ports 65 and 68 on through the pipe 66 to the fluid cylinder 70. The released air will pass through the pipe 66 to the cylinder 70, forcing the piston 71 to the other end thereof beyond the port 70', thus closing the throttle and escaping 130

to the atmosphere the reduction of the train line, pressure will operate the triple valves and the said brakes.

Briefly describing my invention, it may be mentioned that the railway track will be divided into sections or blocks that are insulated from each other and each block is electrified at all times unless a switch is open or there is a wash out, or there is a train 10 occupying the block. In Fig. 11 will be seen a diagrammatic view of the track circuit 50* of a single block in which is arranged the magnet 35* and the solenoid 120, hereinbefore referred to, of the train operated trip 15 mechanism.

In practice, the train operated trip mechanism will be located slightly in advance of the block, by which it is controlled so that the likelihood of the train tripping itself 20 will be wholly avoided. Now considering the block to be clear, the pin 30 of the clutch lever 29 will rest at the bottom of the slot 31 and the magnet 35* and the solenoid 120 will be energized. Just before the train enters 25 the block, the first wheel of the train or locomotive will come into contact with the link members 48 causing the bar 43 to descend and revolve the shaft 12 which through the medium of the large gear segment 18 30 will cause the shaft 18 carrying the gear segments 21 and 20 to revolve at a greater rate of speed. Since the segment 17 is loose upon the shaft it will be obvious that it can revolve at the same rate of speed as the segment 20 whereby the blocks 22 may be elevated with rapidity into an operative position. The hook 50 carried by the rack bar in descending forces the pin 30 over to allow it to pass, after which the pin 30 will be 35 moved back into its original position through the action of the spring 40'. As soon as the first wheel of the locomotive passes the rack bar 43 it will rise, the hook or shoulder 50 thereof raising the pin 30 of 40 the clutch lever 29 to the top of the guide way 31 where it will be moved laterally to rest in a position upon the stop pin 34* through the action of the spring 40, thus holding the clutch open until the magnet 35* 45 is deenergized. The clutch having been opened, the block 22 will immediately descend. When the train has advanced far enough to short circuit the circuit 50*, the magnet 35* and the solenoid 51 will be de- 50 energized, thus allowing the clutch lever 29 to descend into its normal position. Now should another train enter the block while the first train has a block circuit shorted it will lift the block 22 into operating position 55 where it will be locked by the spring actuated solenoid core engaging the recess 123 in the side wall of the block 22. The hook 50, as before, will raise the clutch lever 29, but since the magnet 35* is deenergized it will 60 drop into its normal position.

As a train is passing through the block, each wheel passing over the rail B will depress the bar 43. Assuming that there is no other train located within the block ahead, the magnet 35* and the solenoid 120 will be 70 energized. The effect of this energization upon the movement of the bar 43 and the other movable parts of the track device, upon passage of the first wheel of the preceding locomotive or car, has already been 75 described. It should therefore be apparent that the clutch mechanism mounted upon the shaft 12 will be rendered permanently inoperative, just so long as the track circuit remains unaffected, due to the fact that the 80 pin 30 of the lever 29 is held in suspended position by the locking pin 35 out of the path of movement of the hook 50 carried by the bar 43. In the event that another train is in the block ahead, the electro-magnet 25 85 and the solenoid 120 will be short-circuited thereby causing the movement of the locking pin 35 into inoperative position, thereby releasing the pin 30 of the lever 29 and causing the clutch mechanism to be rendered operative. At the same time the core of the solenoid will be released so as to be moved into operative position by the spring 121. Owing to the operativeness of the clutch mechanism, the block 22 will be raised into its 90 95 operative position in the manner previously described, wherein it will be locked due to the engagement of the said solenoid core within the recess 123. The said block will thus be maintained in a position wherein it 100 will become engaged with the train-carried controlling mechanism. The lifting arms 16 and 19 will be operated continuously, but will have no effect on the block 22, as the latter is held suspended until the solenoid 105 120 is again energized.

From the foregoing description taken in connection with the accompanying drawings, the advantages of construction and the method of operation will be readily apparent to those skilled in the art to which the invention relates, and while I have described the principle of operation of the invention, together with the device which I now consider to be the best embodiment thereof, I desire to have it understood that such changes of construction may be made when desired as are within the scope of the appended 110 115 claims.

Having thus fully described my invention, 120 what I claim as new is:

1. In a safety train controlling block system, a track circuit, means carried by the locomotive operating to set the air brakes, a train operated trip arranged in advance of 125 each block and comprising a vertically movable element, a depressible bar operatively connected with said element, which when depressed operates to elevate the said element into operative position for engagement 130 135

with the locomotive carried means, and means arranged in the track circuit for controlling the movement of the said movable element.

- 5 2. In a safety train controlling block system; an insulated section of track; a track circuit including said section, a train operated trip arranged in advance of the section and comprising a vertically movable element
 10 adapted to be elevated above the rails, train-carried mechanism engageable with the said element, an actuating shaft for the element, means carried by the shaft for supporting the said movable element, means arranged
 15 in the track circuit for controlling the movement of the said shaft, means controlled by a wheel of the train for revolving the actuating shaft to elevate the vertically movable element, and means arranged in the
 20 circuit to automatically lock the movable element in operative position upon deenergization of the said track circuit.

3. In train stopping mechanism, a train operated trip comprising a revolubly mounted shaft, an elevating arm and a gear segment rigid therewith loosely mounted upon the shaft, another gear segment loosely mounted adjacent the first mentioned segment, a clutch for locking the last mentioned segment to the revoluble shaft, a second shaft mounted adjacent the revoluble shaft, a lifting arm and gear segments fixed thereto, said segments meshing with the loosely mounted segments on the revoluble
 35 shaft, movable train controlling means supported upon the said lifting arms, and means controlled by the wheel of a train for revolving the revoluble shaft, to elevate the train controlling means.

- 40 4. In train stopping mechanism; a train operated trip comprising a revoluble shaft, a second shaft, an integral lifting arm and gear segment loosely mounted upon the revoluble shaft, a second gear segment of
 45 greater radius than the first mentioned segment and loosely mounted upon the same shaft adjacent the first mentioned segment, another lifting arm secured fixedly to the second shaft, a gear segment secured to the
 50 said shaft adjacent the lifting arm adapted to mesh with and of the same radius as the first mentioned segment of the revoluble shaft, a second gear segment of smaller radius secured to the second shaft and adapted
 55 to mesh with large gear segment, a clutch for locking the large gear to the revoluble shaft, train controlling means supported upon the said lifting arms, and means controlled by a wheel of the train for revolving
 60 the revoluble shaft to elevate the train controlling means.

5. In a train controlling means, a train operated trip comprising a revoluble shaft, a second shaft loosely mounted adjacent and

parallel with the first mentioned shaft, supporting arms mounted upon said shafts, train controlling means mounted upon the said arms, means upon the said shafts operating to elevate the supporting arms at a greater rate of speed than that of the revoluble shaft, and means operated by the first wheel of the train for revolving the revoluble shaft to elevate the train controlling means.

6. In train stopping mechanism, a train operated trip comprising a revolubly mounted shaft, an elevating arm and a gear segment rigid therewith loosely mounted upon the shaft, another gear segment loosely mounted adjacent the first mentioned segment, a gravity clutch for locking the last mentioned segment to the revoluble shaft, means to maintain the clutch in unlocked position, a second shaft mounted adjacent the revoluble shaft, a lifting arm and gear segments fixed to the second shaft, said segments meshing with the loosely mounted segments on the revoluble shaft, movable train controlling means supported upon the said lifting arms, and means controlled by the wheel of a train for revolving the revoluble shaft to elevate the train controlling means.

7. In train stopping mechanism, a train operated trip comprising a revolubly mounted shaft, an elevating arm and a gear segment rigid therewith loosely mounted upon the shaft, another gear segment loosely mounted adjacent the first mentioned segment and provided on its outer face with clutch teeth surrounding the said shaft, a clutch member keyed to and slidably mounted upon said revoluble shaft, a yoke pivoted medially and connected at one end with the clutch member, a clutch lever pivoted at one end to the opposite end of the said yoke and provided with an adjustable counterbalancing weight adapted to normally maintain the clutch in locked position, a second shaft mounted adjacent the revoluble shaft, a lifting arm and gear segments fixed to the second shaft, said segments meshing with the segments upon the revoluble shaft, movable train controlling means supported upon said lifting arms, and means controlled by the wheel of a train for revolving the revoluble shaft to elevate the train controlling means.

8. In train stopping mechanism, a train operated trip comprising a revolubly mounted shaft, an elevating arm and a gear segment rigid therewith loosely mounted upon the shaft, another gear segment loosely mounted adjacent the first mentioned segment, a second revoluble shaft mounted parallel to the first shaft, a gear segment secured rigidly to the second shaft and being engaged with the last-named gear segment

of the first shaft, a second gear segment mounted fixedly upon the second shaft in mesh with the first gear segment of the first shaft, a train-controlling member supported 5 upon the said elevating arm, a clutch slidably mounted upon the revolute shaft for engagement with the last mentioned segment of the first shaft, a clutch lever pivoted medially and connected with the movable member of the clutch and provided with a counterbalancing weight adapted to normally hold the clutch in locked position, a pinion mounted on the outer end of the revolute shaft, a depressible rack bar for 10 engagement with the pinion and provided with means for lifting the clutch lever, means for raising the said bar, and means to maintain the clutch in unlocked position, said rack bar operating when depressed to 15 rotate the revolute shaft to elevate the train controlling means.

9. In a safety train controlling block system, a track circuit including an insulated section of track, means carried by the locomotive operating to set the brakes, a train operated trip controlled by said track circuit and arranged in advance of the section of track and comprising a revolutely mounted shaft, a lifting arm and a gear segment 20 rigid therewith loosely mounted upon the shaft, another gear segment loosely mounted adjacent the first mentioned segment, a gravity clutch for locking the last mentioned segment to the revolute shaft, a pinion mounted upon the outer end of the revolute shaft, a depressible rack bar engaging the pinion and provided with means for raising the clutch lever, a spring for raising said bar when depressed, and means arranged in the track circuit for maintaining the clutch in unlocked position, a second shaft mounted adjacent the revolute shaft, a lifting arm and gear segments fixed to the second shaft, said segments meshing with 30 the segments upon the revolute shaft, and a movable train controlling means supported upon said lifting arms.

10. In a safety train controlling block system, a track circuit, means carried by the locomotive operating to set the air brakes, and a train operated trip arranged in advance of the rails of each track circuit comprising a revolutely mounted shaft, an elevating arm and a gear segment rigid therewith loosely mounted upon the shaft, another gear segment loosely mounted adjacent the first mentioned segment, a gravity clutch for locking the last mentioned segment to the revolute shaft, a pinion mounted upon the outer end of the revolute shaft, a depressible rack bar for engagement with the pinion and provided with means for unlocking the clutch, a spring for raising said bar, an electromagnet arranged in the track 40 circuit and operating to hold the clutch in unlocked position when the electromagnet is energized, a second shaft mounted adjacent the revolute shaft, a lifting arm and gear segments fixed to the said second shaft, said segments meshing with the loosely mounted segments on the revolute shaft, a movable train controlling means supported upon the said lifting arms, and means arranged in the track circuit and adapted to retain the train controlling means in operative position upon the short circuiting of the track circuit.

11. In a safety train controlling block system, a track circuit, means carried by the locomotive and operating to set the air brakes, a train operated trip arranged in advance of the rails of said track circuit and comprising a revolutely mounted shaft, a lifting arm and a gear segment rigid therewith loosely mounted upon the shaft, another gear segment mounted adjacent the first mentioned gear segment, a gravity clutch for locking the last mentioned segment to the revolute shaft, a pinion mounted upon the outer end of the revolute shaft, a depressible rack bar for engagement with the pinion, means carried by the rack bar for unlocking the clutch upon the ascension of said bar, means for raising said rack bar, an electromagnet arranged in the track circuit and adapted to hold the clutch in unlocked position when the electromagnet is energized, a second shaft mounted adjacent the revolute shaft, a lifting arm and gear segments fixed to said second shaft, said segments meshing with the loosely mounted segments on the revolute shaft, a vertically movable block supported upon the said lifting arms, and a solenoid arranged in the track circuit and adapted to maintain the said block in elevated position upon the short circuiting of the track circuit.

12. In a railway block system, the combination with train carried means operating to set the air brakes, a track circuit, a train depressed member, and means operated thereby for operating said train carried means including a clutch having a weighted clutch operating lever, of means for controlling said clutch comprising a bracket having parallel vertical passages and terminal connecting passages disposed horizontally adapted to receive the outer end of the clutch lever, a pin normally extending across one vertical passage and adapted to support the clutch lever when so positioned, means carried by the train depressed member for moving the clutch lever in position to be thrown upon said pin, bars yieldingly arranged diagonally across the upper and lower portions of said vertical passages and the upper and lower horizontal passages whereby the clutch lever will be moved lat-

erally in opposite directions when it reaches the upper and lower portions of the vertical passages, a normally energized electro-magnet arranged in the track circuit and operating to normally hold the pin across said passage, and means acting to retract said pin upon deenergization of the magnet.

In testimony whereof I affix my signature in presence of two witnesses.

LOUIS LONG.
